UNITED STATES PATENT OFFICE.

FLORENCE E. CORY, OF NEW YORK, N. Y., ASSIGNOR TO VANDEVENTER & HORNE, OF SAME PLACE.

DESIGN FOR A CARPET.

SPECIFICATION forming part of Design No. 14,839, dated March 4, 1884.

Application filed January 28, 1884. Term of patent 3½ years.

To all whom it may concern:

Be it known that I, FLORENCE E. CORY, of the city and State of New York, have invented a new Design for Carpets, of which the following is a specification.

In this design the ground is mottled, and there are bunches of leaves placed quincunxially in the pattern, as represented in the photograph. The larger leaves are reticulate and variegated, as at *a a*. The smaller leaves are pinnate, as at *b b*, and there are sprigs, as at *c*.

I claim—

The design for a carpet, consisting of the bunches of leaves upon a mottled background, as described and represented.

Signed by me this 22d day of January, A. D. 1884.

FLORENCE E. CORY.
